[57] CLAIM

The ornamental design for a seat caddy, as shown and described.

DESCRIPTION

FIG. 1 is a top perspective view of a seat caddy showing my new design, it being understood that the broken lines are shown for illustrative purposes only and form no part of the claimed design;

FIG. 2 is a right side elevation view thereof, the left side being a mirror image thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a top plan view thereof with the lid in raised condition, illustrating the interior surfaces.
